ATTORNEYS.

UNITED STATES PATENT OFFICE.

SALLY SALINGER, OF NEW YORK, N. Y.

POCKET ATTACHMENT.

SPECIFICATION forming part of Letters Patent No. 476,687, dated June 7, 1892.

Application filed February 1, 1892. Serial No. 419,944. (No model.)

To all whom it may concern:

Be it known that I, SALLY SALINGER, of New York city, in the county and State of New York, have invented a new and Improved 5 Safety Attachment for Pockets, of which the following is a full, clear, and exact description.

The object of the invention is to provide a new and improved safety attachment for use in the ordinary garment-pockets, and which 10 is simple and durable in construction and arranged to be easily attached to or detached from the garment-pocket.

The invention consists of certain parts and details and combinations of the same, as will 15 be fully described hereinafter, and then pointed out in the claims.

Reference is to be had to the accompanying drawings, forming a part of this specification, in which similar letters of reference indicate 20 corresponding parts in all the figures.

Figure 1 is a side elevation of the improvement with the top bag open. Fig. 2 is a sectional side elevation of the same on the line 22 of Fig. 1, and as applied. Fig. 3 is a sectional plan view of the same on the line 33 of Fig. 1, and Fig. 4 is a plan view of a modified form of frame.

As shown in Figs. 1 and 2, three bags A A' A² are connected and suspended within a garment-pocket. The upper bag A is alone attached to the said garment-pocket, and the other two bags A' A² are suspended from the first bag A by means that will be presently described. The body B of each bag may have 35 a partition B' and is provided with a metal jaw-frame C, having a suitable locking device D. One of the hinged jaws of frame C is constructed with two slots, (see Fig. 1,) and lugs H and I are arranged on opposite sides 40 of such slots, as shown best in Fig. 3. These lugs are preferably formed integrally with the jaw and perforated to adapt them to receive the devices E, which secure the bag to a garment. The devices consist of pairs of 45 pins connected by a cross-bar G and adapted to slide in said lugs H and I. In fastening the bag A to a garment-pocket, as shown, the pins E pass through a portion of it, which, for that purpose (see Fig. 3) is drawn into the 50 opening J, between the said parts H and I.

Thus, a bag—in this case the upper bag A—is detachably secured to the garment-pocket, and the others A' and A² are suspended from it.

In order to connect the bags A, A', and A² with each other, as shown in Fig. 1, the bags 55 A and A' are formed at their lower ends with eyes K, and similar eyes L are formed on the frames C of the bags A' and A², the said eyes L being located directly opposite the eyes K and connected with the same by rings N, 60 adapted to be opened and closed in the usual manner. The rings employed are preferably sectional and held closed by springs or other means. By opening the rings N the several bags can be readily detached from one another and the detached bag can then be used 65 independently of the others in another garment-pocket, if desired.

It will be noted (see Fig. 2) that the fastening device E, that attaches the upper bag 70 A to the side of the garment-pocket, and the connecting devices K N L are all applied on the same (the left) side of the bags, so that all the bags hang in line against one side of the garment-pocket, thus leaving the other (right) 75 side free to provide convenient access to the mouths of the suspended pockets A' and A².

The metal frame of one bag A² (see Fig. 4) is formed with an outward bend C', located near the middle, the frame C being in such 80 case provided with two locking devices D, arranged on opposite sides of the said bend C'. This bag A² is more especially designed for use in vest-pockets to support and hold a watch, the chain of which extends through 85 the bend C'.

By having the two locks D at opposite sides of the bend C' the watch cannot be removed from the bag when the frame C is closed, thus preventing unauthorized persons from 90 drawing the watch out of the bag.

If the several bags A A' A² are connected with each other, as shown in the drawings, then only the uppermost bag A is attached by its fastening device E to the garment-pocket F, the bag A' being suspended from the bag A and the bag A² from the bag A'. The several bags can be used for various purposes, the upper bag being principally designed for containing change, as previously 100

mentioned, the second bag A' for receiving bills, and the third A² for papers or valuable documents, jewelry, or other articles.

Having thus described my invention, what I claim, and desire to secure by Letters Patent, is—

1. A safety attachment composed of hinged jaws, one of which is provided with slots and perforated lugs II I, located on opposite sides of each slot, and pins E, adapted to slide in each pair of said lugs, for attaching the frame to a garment-pocket, as shown and described.
2. In a safety attachment, the combination,

with a garment-pocket F, of a bag A, having a device E for fastening it to the garment-pocket, a second bag A' and the devices consisting of the ears K L and ring N, which detachably connect it to the upper bag A, the said devices being applied on the same side as the device that secures the upper bag to the garment-pocket, as and for the purpose specified.

SALLY SALINGER.
